UNITED STATES PATENT OFFICE.

HENRY FAIRBANKS AND HOWARD PARKER, OF ST. JOHNSBURY, VERMONT.

MACHINE FOR FORMING BODIES FROM PULP.

SPECIFICATION forming part of Letters Patent No. 557,197, dated March 31, 1896.

Application filed November 27, 1893. Serial No. 492,081. (No model.)

To all whom it may concern:

Be it known that we, HENRY FAIRBANKS and HOWARD PARKER, of St. Johnsbury, in the county of Caledonia and State of Vermont, have jointly invented certain new and useful Improvements in Machines for Forming Bodies from Pulp, of which the following, taken in connection with the accompanying drawings, is a specification.

10 This invention relates to the class of apparatus employed to take a layer of wet pulp from a supply of the same in suspension and transfer it while being partially dried to a roll or form, around which it is wound.

15 Our improvements, as herein represented, are especially adapted to the formation of tapering bodies from successive layers of pulp taken from a tank by an obliquely-placed straining and carrying wheel; but some of 20 the novel features are equally applicable to cylindrical forms.

The several features of our invention are hereinafter fully described with reference to the drawings, and are particularly referred 25 to in the appended claims.

In the drawings, Figure 1 is an elevation, partly in section and with parts broken away, of a machine embodying our improvements. Fig. 2 is a vertical central section of the same. 30 Figs. 3 and 4 are details of the preferred form of couch-roller and shield or air-stop.

A represents a pulp-tank, and B an educt or water-passage leading from the lower part thereof and formed with a broad arc-shaped 35 mouth, extending in a curve from the pulp-level on one side of the tank to the same level on the other side. (See Fig. 1.)

C is an inclined wheel revolving with its shaft D in suitable bearings E and driven by 40 a worm F and gear G or any other convenient power and at proper speed.

The wheel C has upon its face between two concentric rings C², adjacent to its periphery, an annular reticulated portion C', upon which 45 the pulp is deposited in a suitably thick layer by the suspending water escaping from the tank through the educt B, this annular portion of the moving wheel continually presenting a fresh part of its screen-surface to admit 50 the water to but exclude the pulp from the arc-shaped mouth of the educt. To resist this pressure, the gauze-ring C' is supported

by a succession of transverse rods c, strained across and spanning the space between the concentric rings C² of the carrying-wheel. 55 The pulp is taken up on the gauze-surface, the water gradually escaping through its meshes and passing freely between the rods c. The back of the two rings C² of the carrying-wheel bears for support against a packing along the curved mouth of the educt, which prevents escape of the pulp. Additional supports may be provided opposite to the couch-roller and at other points. The slow rotation of this wheel C well serves to 65 keep the pulp in suspension. The wires or rods C, strained like the spokes of a bicycle-wheel, give sufficient strength and, being near together, furnish support to the gauze-ring much as in the ordinary mold wheel or roll 70 the peripheral gauze of the cylinder is supported by the parallel wires beneath it.

H represents the couch-roll, in this instance of frusto-conical form, and adapted to revolve in surface-contact with the annular gauze 75 portion of the wheel C. The couch takes from the gauze the layer of semiliquid pulp and transfers it to the press-roll or form I, which is also in rolling contact with the couch.

We prefer to employ two or more forms I, 80 as heretofore practiced, arranged to come successively into action, so that when a sufficiently thick body or sleeve of the material has been formed by winding several films of the pulp around one form another form may 85 be brought into position, and the action of the machine may proceed while the formed body is being removed from the first form.

The couch-roll should for the best results be hollow with its entire periphery finely perforated, and a strong suction through such perforations draws the water from the pulp layer into and away from the roll. For this purpose a suction-fan J, having obliquely-placed blades and driven at a high speed is 90 preferred, and we have combined such a spiral or screw fan with the couch and carrying-wheel with excellent results. One end of the couch H is closed while the other is an open or skeleton frame. Closely adjacent to this is 95 the case K in which the fan J revolves, driven by the pulley L on shaft M and serving to extract a large percentage of the moisture remaining in the pulp layer. The fan-blades 100

may be partly within the end of the suction-couch. The water so withdrawn is discharged through a pipe N.

A portion of the surface of the couch-roll 5 carries no pulp, and is furnished with a stop or shield S to prevent the inlet of air through the perforations. Such shield forming a segment of a truncated cone is preferably internal and secured to the stationary axle h 10 around which the couch revolves, but may be external and secured to the frame. In either case it is suitably packed with relation to the moving couch to exclude air without causing unnecessary friction.

15 The couch-roll (more particularly represented in the detail Fig. 3) is of novel construction. It is formed with a body of metal, preferably covered with hard rubber, to which are cemented or vulcanized narrow peripheral 20 rings of yielding soft rubber forming flanges, and between these flanges or rings the hard body of the shell is perforated with circumferential rows of holes so close together as to allow free passage for water from the grooves 25 between the flanges into the interior of the roll.

We sometimes omit the hard rubber and vulcanize or cement the soft rubber directly upon the metal body. We prefer to finely 30 serrate the yielding surface to better facilitate the passage of the water pressed from the pulp layers. The covering straining-cloth which encircles the couch as a sleeve in the usual way is thus held upon a series of points. 35 Holes through the soft rubber would be closed by pressure, but the grooves between the flanges allow the free passage of water strained through the covering-cloth into the interior of the roll, and the changes of form 40 under pressure will assist to wash out all clinging fibers of pulp.

The drawings represent a bearing M' for the fan-shaft M at the end of a non-rotating stud or bar O inserted axially into the hollow 45 shaft D of the carrying-wheel. A stop-pin through one side of said shaft enters a groove in said stud and holds it against withdrawal. A bearing supported by suitable framework secured to the tank may be substituted, if 50 preferred. The shaft M is represented as tubular and revolving around the stationary axle of the couch-roll.

It is obvious that our perforated couch with elastic flanges may be of cylindrical form and 55 adapted for use with various kinds of wet machines, also that the spiral exhausting-fan

and the air stop or shield may with equal advantage be applied to cylindrical couches.

We claim as our joint invention—

1. The tank A adapted to contain pulp in 60 suspension and provided with the educt B, in combination with the carrying-wheel G, having an annular gauze portion forming a continuous screen closing the educt to the passage of pulp, substantially as set forth. 65

2. A pulp-tank provided in its lower portion with a water-passage, and an oblique carrying-wheel having an annular permeable portion caused to revolve within said tank and to take up a layer of pulp at the mouth of 70 such passage, in combination with a suitable couch-roll and a forming or pressing roll, substantially as set forth.

3. A tank adapted to contain pulp in suspension and provided with an educt for escape of the suspending water, and an oblique carrying-wheel revolving in said tank and having near its periphery a gauze annulus forming a movable screen between the tank proper and said educt, in combination with 80 a hollow, perforated, suction couch-roll adapted to transfer the layer of pulp from said annulus to the forming or pressing roll, and to extract the water therefrom during such transfer, substantially as set forth. 85

4. The wheel C having concentric rings C², the inner ring being directly connected with the axle, and the outer one joined to the inner one by a closely-set series of radial wires c, strained across the intermediate space, in 90 combination with a gauze annulus resting directly on said wires, substantially as set forth. 95

5. A suction couch-roll, having a hollow body, through the hard periphery of which are numerous perforations arranged in circumferential rows, between which rows are annular flanges of soft compressible rubber, standing out from the hard body of the roll, which under pressure nearly meet to make the yielding surface of the roll continuous, but 100 which being circumferential, cannot fold over to close the holes, these several parts in combination with each other as specified.

In testimony whereof we have signed our names to this specification in the presence of 105 two subscribing witnesses.

HENRY FAIRBANKS.
HOWARD PARKER.
